INVENTOR

John W. Will
John A. Brimith
BY
ATTORNEY

UNITED STATES PATENT OFFICE.

JOHN W. WILL, OF SAN JOSE, CALIFORNIA.

PORTABLE PRESSURE OILER.

Application filed March 3, 1921. Serial No. 449,471.

To all whom it may concern:

Be it known that I, JOHN W. WILL, a citizen of the United States, and resident of San Jose, in the county of Santa Clara 5 and State of California, have invented certain new and useful Improvements in Portable Pressure Oilers, of which the following is a specification.

My invention has for an object to provide 10 a portable receptacle and a supporting bracket, permanently connected thereto, which will be of a practical nature in dispensing a lubricant or other liquid.

In the drawing:—

15 Figure 1 is a side elevation of the device embodying my invention, parts being broken away.

Figure 2 is a detail plan view of a portion 20 of the suspension means forming a part of the invention.

At 6 I show a cylinder of suitable dimensions and of suitable material to withstand considerable internal pressure, the same being threaded at its upper end as at 7 to 25 engage a threaded cap 9. Cap 9 is provided with a pet-cock at 10 through which the pressure within the cylinder is reduced, and a tube 11 having a valve 12 therein and a hose 13 attached thereto. Cap 9 also has 30 a filling plug 14 arranged therein as shown.

The lower end of cylinder 6 is also threaded at 15 to engage a threaded bottom member 16 having a downwardly extending flange 17. A discharge tube 18 is fitted into 35 the power portion of cylinder 6 as shown and fitted with a valve 19 and has a hose 20 attached thereto, the said hose being provided with a union at its end 21 and a pet-cock at 22.

40 At 23 I show a flat metal bar passing diametrically across the bottom member 16 and secured thereto and extending a distance beyond both sides thereof and thence upwardly in parallel relation to cylinder 6 and spaced a distance therefrom as at 45 24—24, to a point a distance above the upper end thereof. One side portion 24 is then carried diametrically across the top 50 of the device as at 25 and joined to the other side member 24, the latter being carried a distance upwardly beyond cross mem-

ber 25 as at 26 and bent into a hook 27. This frame constitutes a hanger or support for the cylinder. Tube 11 passes through portion 25 of bar 23 and serves to assist 55 in maintaining the same in its proper relation to cylinder 6.

In its practical application the cylinder is partially filled with a quantity of lubricating oil. It is now carried to a point 60 adjacent to the device or part to be lubricated to which the hose 20 is attached by means of union 21. Hose 13 being connected to a suitable source of air pressure (not shown) the valves 12 and 19 and 65 petcock 22 are opened. The air under pressure entering cylinder 6 forces oil through hose 20 to the part to be lubricated.

When the device is not in use the hose may be wrapped around cylinder 6 as indicated at 28, the bar 24 affording protection thereto as well as providing a handle and hook for the device. This structure as disclosed is simple in form, construction and operation, economical to manufacture 70 and highly efficient in its practical application.

It is to be understood that while I have herein shown and described one specific embodiment of my invention, changes in 75 form and details of construction may be made within the scope of the appended claim.

I claim:—

A receptacle support of substantially rectangular form having two of its parallel sides extending lengthwise of the receptacle on opposite sides thereof and in spaced relation thereto, one of the remaining sides of the support being interlocked with the 80 bottom wall of the receptacle, a top bar in said support, said top bar provided with an aperture accommodating a rigid tube from the receptacle whereby a rigid connection between the receptacle and the support is made; an apertured vertical member in the support, said vertical member admitting a conduit communicating with the receptacle, the conduit serving to maintain a rigid connection between the support 85 and the receptacle.

JOHN W. WILL.
